[57] CLAIM

The ornamental design for an entry pool for an amusement water slide, as shown.

DESCRIPTION

FIG. 1 is a perspective view of an entry pool for an amusement water slide showing my new design.

FIG. 2 is a top plan view of the entry pool.

FIG. 3 is a longitudinal sectional elevation taken substantially on line 3—3 of FIG. 2.

FIG. 4 is a side elevation of said entry pool.

FIG. 5 is a rear end elevation of the same.

FIG. 6 is a front end elevation of the entry pool; the view looking rearwardly thereinto through the front opening.
